UNITED STATES PATENT OFFICE.

FLOYD J. METZGER, OF NEW YORK, N. Y., ASSIGNOR TO CALIFORNIA CYANIDE COMPANY, INCORPORATED, OF NEW YORK, N. Y., A CORPORATION OF DELAWARE.

METHOD OF MAKING ALKALI-METAL CYANIDE.

Application filed March 25, 1924. Serial No. 701,736.

To all whom it may concern:

Be it known that I, FLOYD J. METZGER, a citizen of the United States, residing at New York city, in the county of New York, State of New York, have invented certain new and useful Improvements in Methods of Making Alkali-Metal Cyanide; and I do hereby declare the following to be a full, clear, and exact description of the invention,

10 such as will enable others skilled in the art to which it appertains to make and use the same.

This invention relates to the fixation of nitrogen by heating mixtures of alkali metal compounds and carbon with or without a catalyzing agent in the presence of nitrogen or nitrogenous gases, and particularly to an improved method whereby the production of alkali metal cyanide is assured.

20 A method of fixing nitrogen is described in United States Letters Patent No. 1,322,195 and involves the heating of mixtures of alkali metal carbonates or oxides with carbon and relatively small amounts of iron, preferably in the form of iron oxide, in the presence of nitrogenous gas. As little as two per cent of iron is effective and small amounts are used preferably so that the capacity of the reaction chamber will not be

25 reduced by the presence of surplus and inactive material. The furnace product consists of alkali metal cyanide combined with other alkali metal compounds and carbon. The cyanide may be recovered by leaching the product with suitable solvents but preferably the product is treated with carbon dioxide under regulated conditions to release hydrocyanic acid which is condensed as a liquid.

30 In conducting the process a nitrogenous gas containing a relatively high proportion of nitrogen is preferred. In practical operations the nitrogen can be obtained from a liquefaction apparatus but a less expensive and more readily available source is found in the gases which escape from the heating furnace which is employed to maintain the

temperature of the reaction. The furnace gases are scrubbed to remove carbon dioxide therefrom and the balance, which is principally nitrogen, is delivered to the retort in which the cyanide reaction is carried out. The nitrogenous gas, whether derived from a liquefaction apparatus or from furnace gases, usually contains more or less oxygen.

At the high temperatures which are necessary in the reaction zone where the cyanide is formed oxygen has no deleterious effect upon the reaction, particularly in the presence of carbon. At lower temperatures, that is to say, below substantially a red heat, the oxygen is undesirable since it combines with the cyanide to form a cyanate. The cyanate cannot be separated readily from the cyanide if the product is leached and it is not decomposed by carbon dioxide to produce hydrocyanic acid. It consequently represents a loss of cyanide and reduced efficiency of the process regardless of the manner in which the cyanide is recovered from the furnace product.

It is the object of the present invention to provide a process of fixing nitrogen which is capable of operation at maximum efficiency and particularly to avoid the production of alkali metal cyanate in the furnace product.

In carrying out the invention the reaction is preferably conducted in a tubular reaction chamber or retort which is adapted to be rotated and which is heated externally by means of a suitable furnace supplied, for example, with oil burners or other means of generating combustion gases capable of producing a temperature of from 950 to 1100° C. The portion of the reaction chamber in which the reaction occurs is completely filled with the mixture of carbon and alkali metal compound with or without a catalyst such as iron. The complete filling of the reaction chamber ensures the proper contact of the nitrogenous gas with the mixture, particularly when the mass is

tumbled by rotating the reaction chamber. The rotation of the reaction chamber is continued during the entire period while the reaction is being carried on and causes the particles to constantly shift their positions, expose fresh surfaces to the action of the gas and prevent channeling. The mixture is heated meanwhile to the temperature of the reaction preferably in the neighborhood of 1100° C. by the heating gases which surround it, the heat being conducted through the walls of the reaction chamber and through the material therein so that all of the material is at substantially the same temperature. The rotation of the reaction chamber ensures uniformity of heating.

The nitrogenous gas is introduced at the lower end of the reaction chamber and proceeds through the mass of material therein to the upper or outlet end where it consists largely of carbon monoxide and from which it is discharged to the atmosphere. At its lower end the reaction chamber extends for some distance beyond the wall of the combustion chamber in order that proper bearings for the tube may be maintained. This extension is considerably cooler than that portion of the tube which is within the combustion chamber and if the mixture were permitted to descend into the extension it would cool rapidly particularly if the nitrogenous gas were introduced directly at the end of the tube.

This cooling of the furnace mixture in the presence of nitrogenous gas has no disadvantage if the gas is substantially free from oxygen. On the other hand, the presence of oxygen in contact with the furnace product at low temperatures results in the formation of cyanate. To avoid this difficulty I introduce a plug or "plunger" into the lower end of the tube and arrange it so that the contents of the tube cannot descend substantially beyond the wall of the combustion chamber. The plunger is provided with passages through which the nitrogenous gas is delivered to the furnace mixture above the plunger and first contacts with the mixture accordingly at a temperature at which alkali metal cyanates cannot exist. By maintaining the furnace mixture with which the nitrogenous gas first contacts always at a temperature above that at which alkali metal cyanate can exist, I avoid the formation of cyanate in the mixture and thus materially increase the efficiency of the process.

In the accompanying drawing an apparatus which is adapted for use in conducting the process is illustrated in longitudinal section.

Referring to the drawing, 5 indicates a furnace constructed of brick work or other suitable material and preferably having a

refractory lining 6 enclosing a combustion chamber 7. A suitable fuel, in this instance producer gas, may be supplied from a gas producer 8 to a passage 9 from which the gas is delivered through gas inlets 10 to the combustion chamber 7 where the gas is mixed with air and is burned to produce the necessary high temperature. The combustion products pass over a bridge wall 11 and are withdrawn from the chamber, preferably passing an economizer (not shown). No surplus heat is employed in preheating the air which is mixed with the gas before combustion thereof. Reference is made to Letters Patent No. 1,322,195 above referred to for the details of this arrangement.

A tube 12, preferably of oxidation-resistant material such as an alloy containing nickel and chromium, is disposed in suitable openings in the walls of the furnace 5 to occupy an inclined position. The tube is provided with flanges 13 and 14 resting on rollers 15 and 16. The flange 14 bears against a thrust roll 17 which maintains the tube in proper position in the furnace. The tube may be rotated by means of a chain 18 engaging a sprocket 19 thereon and a sprocket 20 on a shaft 21 which may be actuated in any suitable manner.

The tube 12 is filled with the furnace mixture from the upper end which is open as indicated in the drawing. The lower end of the tube is preferably closed by a head 22 bolted or otherwise secured to a flange on the tube. To prevent the travel of the furnace mixture beyond that portion of the tube which is heated by the furnace a plunger 23 is inserted in the end of the tube. The plunger 23 has an extension 24 with a passage 25 which communicates through a pipe 26 with a flexible tube 27 through which the nitrogenous gas is introduced. The pipe 26 passes through a gland 28 so that the tube 12 may rotate while the pipe 26 remains stationary. The nitrogenous gas is delivered through the passage 25 to the furnace material. The latter cannot descend beyond the lower limit of the heating zone and consequently cannot cool to a temperature lower than that of the reaction. Thus all of the reacting mass is held at the proper temperature to preclude the formation of cyanate.

At the conclusion of the reaction the head 22 and plunger 23 are removed and a portion of the furnace product is withdrawn, that portion which is held in the preheating zone being permitted to descend into the reaction zone. The plunger and head are replaced and the operation is continued.

Various changes may be made in the details of operation as hereinbefore described without departing from the invention or sacrificing any of the advantages thereof.

I claim:—

The method of fixing nitrogen, which comprises filling a reaction chamber with a mixture containing an alkali metal compound and carbon, heating the mixture in the reaction chamber to a temperature at which nitrogen combines therewith to form alkali metal cyanide, passing nitrogenous gas containing oxygen from one end of the reaction chamber through the mixture and preventing initial contact of the nitrogenous gas with the mixture at a temperature substantially lower than that maintained in the reaction chamber, thereby avoiding oxidation of the alkali metal cyanide in the mixture to form cyanate. 10 15

In testimony whereof I affix my signature.

FLOYD J. METZGER.
